JOHN E. DOMAGALL, OF PERU, ILLINOIS, ASSIGNOR TO W. H. MAZE COMPANY, OF PERU, ILLINOIS, A CORPORATION OF ILLINOIS

GLAZIER'S POINT SETTER

Application filed November 5, 1928. Serial No. 317,202.

This invention relates to diamond point setters for driving glaziers' points.

The main objects of this invention are to provide an improved form of setting tool or driver which will set the glazier's point tightly and snugly against the glass; to provide a driver which can be used for setting glazier's points on exceptionally small panes of glass; and to provide a generally improved and efficient device of this character.

An illustrative embodiment of this invention is shown in the accompanying drawings, in which:

15 Fig. 1 is a view partly in vertical longitudinal medial section and partly in elevation of the improved driver in position on a fragmentary portion of a window frame.

20 Fig. 2 is a fragmentary view in elevation of the lower front portion of the driver supported on a pane of glass.

Fig. 3 is an enlarged fragmentary detail of the same looking to the right of Fig. 2.

25 Fig. 4 is a fragmentary sectional detail taken on line 4-4 of Fig. 2.

Heretofore in the construction of glazier's point setters, the devices have been constructed so that the front driving end of the ram which drives the glazier's point either 30 rests upon the glass when in position for use or is spaced above the glass the thickness of a front cross bar of the supporting frame. Both of such constructions are unsatisfactory in that where the driving ram rests upon the glass and the machine is supported thereby, forward or driving movement of the ram will cause the front end of the device to jump, and very often the glazier's point will not be set so as to be in snug 35 relationship to the surface of the glass, therefore the pane is loosely fastened in the frame.

In the case where the front end of the driver is supported by a transverse cross 45 strip, the glazier's point is always set in the cross bar of the window frame in slightly spaced relation to the glass and there also the glass is only loosely fastened in the frame.

50 Another objection to prior art devices has

been in the provision of the supporting foot or leg at the extreme rear end of the driver. When drivers of such construction are used for setting points on extraordinarily small panes of glass, the rear supporting foot extends over into the next frame space and if no pane of glass is set therein, then no support is provided for the driver; and even if there is a pane of glass in the adjacent frame portion, such pane may not be on a 55 true level with the pane which is being fastened by the driver.

After many years experience in using various types of prior art setters of this character, I have found that in order to secure 60 a pane of glass snugly and tightly in a frame when using a glazier's point driver it is essential that the position of the device be determined solely by the surface of the pane 65 of glass which is being fastened in the frame. In my present construction, the supporting legs of the driver have been so arranged that the entire weight of the device 70 and its position when in use is determined solely by the pane of glass being glazed and 75 in this manner I secure a very high-grade tight-fitting job of glazing.

In the construction shown in the drawings, the driver comprises a hollow handle 1 which is preferably constructed from two parts longitudinally split and secured together. A magazine 2 is integrally formed at the front end of the handle 1 for carrying a quantity of diamond shaped glazier's points 3, which are normally yieldably urged 80 and pushed downwardly in the magazine by a plunger 4 vertically slidable in a yoke 5. The lower end of the plunger 4 is disposed axially within the magazine 2. The yoke 5 is pivotally mounted adjacent the top end 85 of the magazine and is swingable in a forward direction so as to clear the top open end of the magazine. The upper end of the plunger 4 is surrounded by a helical tension spring 6 which has one end thereof secured 90 to yoke 5 and the other end secured to a head 7 mounted on the upper end of the plunger 4. The spring 6, plunger 4 and yoke 5 are so proportioned that the plunger 95 may be withdrawn upwardly out of the mag-

azine so that the yoke and plunger may be swung forwardly to clear the top end of the magazine.

The lower end of the magazine 2 is normally closed by a thin steel driving ram 8 which has the lateral marginal edges turned back upon themselves to form guideways which embrace laterally extending guides 9 and 10. The guides 9 and 10 are integrally formed at the lower end of the magazine and extend horizontally longitudinally of the driver. The rear end of the driving ram is mounted upon a driving block 11 which has a horizontally rearwardly extending plunger rod 12 rigidly pinned thereto at its front end. The rear end of the rod 12 is slidable through a depending bracket 13 integrally formed on the handle 1 and a helical compression driving spring 14 surrounds the rod 12 and bears between the block 11 and the inner side of the bracket 13.

Means are provided for retracting the block 11 rearwardly against the action of the spring 14 a sufficient distance to uncover the bottom of the magazine 2, and comprises a trigger 15 pivotally mounted by a pin 16 at the front end of the handle 1 immediately behind the magazine 2. The trigger 15 is in the form of a bell crank, the other arm 17 of which depends from the point of pivotal mounting, and a vertically disposed steel strip 18 is riveted or otherwise suitably secured to the lower end thereof. The lower tip end of the strip 18 abuts against the front end of a horizontally disposed pawl 19 pivotally mounted by a pin 20 in a medially disposed longitudinally extending channel formed in the upper side of the block 11.

A helical compression spring 21 is provided underneath the pawl 19 at the front end thereof and bears between the underside of the pawl and the floor of the channelway within which the pawl is mounted. A set screw 22 is threaded through the rear end of the pawl 19 for adjustably positioning the front end of the pawl with respect to the lower end of the plate 18, the pawl having rocking movement on its pivot.

The trigger 15 is provided with an upwardly and rearwardly extending arm 23 which bears against a flat spring 24 mounted within the handle 1 for normally urging the trigger 15 to the position shown in Fig. 1.

At each side of the front end of the device 55 there is provided supporting legs 25 and 26 which are rigidly secured by screws 27 to the sides of the vertically extending portion of the framework within which is contained the magazine 2. These supporting legs are 60 of L shape with the vertical portion secured to the frame of the device and the horizontal portion thereof extending rearwardly and bowed outwardly as shown at 28. These supporting legs are positioned and arranged on 65 the device so as to support the driving ram

8 in very slight spaced relationship to the surface of the pane of glass upon which the driver rests, as shown most clearly in Fig. 3.

In the operation of this device, the head 7 of the plunger 4 is grasped and drawn outwardly until the lower end of the plunger is withdrawn from the magazine 2, at which time the plunger and its supporting yoke 5 are rotated forwardly so as to clear the upper end of the magazine. A package of diamond shaped glazier's points is then placed in the magazine and the yoke and plunger swung back to a vertical position, at which time the plunger is released thus permitting the spring 6 to yieldingly urge the lower end 80 of the plunger 4 down onto the top of the glazier's points within the magazine.

When it is desired to glaze a pane of glass, the driver is placed upon the pane with the front end thereof abutting the cross bar of 85 the window. It is to be noticed that the arrangement is such that the entire device is supported upon the pane of glass being glazed, even though the pane be of small size, the plunger 12 and its driving spring 14 being in spaced relation above the glass so as to clear any intervening cross bar, as shown particularly in Fig. 1.

The handle 1 is grasped by the user with the fingers thereof passing around the trigger 15. The trigger 15 is drawn upwardly by the fingers thus causing the bell crank arm 17 and plate 18 to push the driving block 11 rearwardly against the action of compression spring 14. The block 11 is supported by the 100 rear end of the rod 12 passing through the bracket 13 and the front end of the driving ram 8 being slidably mounted on the guides 9 and 10.

When the trigger 15 has been raised to a 105 certain point, the lower end of the strip or plate 18 slips off of the forward end of the pawl 19, thus permitting the compression driving spring 14 to drive the block 11 forwardly. During the time of retraction of 110 the block 11, a glazier's point has been fed downwardly by the plunger 4 out of the lower end of the magazine 2 in position to be engaged by the front end of the ram 8. This front end of the ram 8 is provided with a 115 V-notch of the same conformation as one-half of the diamond shape glazier's point. Forward movement of the block 11 and ram 8 causes the ram to engage the glazier's point which has been fed down and drive it into 120 the cross bar of the window frame. As the clearance of the ram 8 is very slight with respect to the pane being glazed, the driven point is put in position snugly against the surface of the glass.

The trigger 15 is then released and the spring 24 tends to rotate it in a right hand direction, as viewed in Fig. 1 of the drawings, thus causing the plate 18 to contact with the upper surface of the pawl 19 and depress 130

the same against the action of the compression spring 21. When the trigger 15 has assumed its original position, the plate 18 will have passed the outer end of the pawl 19 5 and said pawl will again resume its normal horizontal position by the action of the compression spring 21. Adjustment of the front end of the pawl with respect to the strip 18 may be secured by rotation of the set screw 10 22 in the appropriate direction. This adjustment will vary the stroke of the ram within reasonable limits.

Although but one specific embodiment of 15 this invention has been herein shown and described, it will be understood that numerous details of the construction shown may be altered or omitted without departing from the spirit of this invention as defined by the following claims.

20 I claim:

1. A device of the class described comprising a frame having a glazier's point magazine therein, a ram for driving glazier's points slidably mounted on said frame, a rearwardly extending rod on said ram, a driving spring for actuating said ram, a manually operable trigger pivoted on said frame for retracting said ram against the action of said driving spring, and L-shaped supporting legs attached to opposite sides of said device, the horizontal portions of said legs forming the sole support of said device.

2. A device of the class described, comprising a frame having a vertically disposed glazier's point magazine therein, a ram slidably mounted on said frame normally closing the lower end of said magazine, said magazine being open at the top end thereof, a yoke pivotally mounted on said frame adjacent the top end of said magazine, a plunger rod slidably carried by said yoke and extending axially within said magazine, and yielding means for normally urging said plunger downwardly in said magazine, said yoke and plunger 45 being swingable to clear the top end of said magazine when said plunger is withdrawn from said magazine.

3. A device of the class described comprising a frame having a glazier's point magazine therein, a ram for driving glazier's points slidably mounted on said frame, a rearwardly extending rod on said ram, a driving spring for actuating said ram, a manually operable trigger pivoted on said frame for 50 retracting said ram against the action of said driving spring, and L-shaped supporting legs having their vertical portions attached to said frame at opposite sides thereof and their horizontal portions extending rearwardly and outwardly to form the sole support of said device.

4. A device of the class described comprising a frame having a glazier's point magazine therein, a ram for driving glazier's points, said magazine being open at the outer

end thereof, a yoke pivotally mounted on the frame adjacent the outer end of said magazine, and a plunger rod slidably carried on said yoke and extending axially within said magazine, said yoke and plunger being swingable to clear said outer end of the magazine when said plunger is withdrawn from said magazine.

In testimony whereof I have hereunto set my hand at Peru, Illinois, this first day of November, 1928.
